A CORPORATION OF OHIO

WINDOW GUIDEWAY

Application filed September 24, 1927. Serial No. 221,821.

The invention relates to window guideways and refers more particularly to guideways for sashless windows adapted for use especially in vehicles. The invention has for 5 one of its objects to so construct a guideway that it opposes the minimum possible frictional resistance to the movement of the window and at the same time provides a good seal and takes care of large variations in the 10 thickness and width of the window and in the distances between the frame members in which the window is slidably mounted. With these as well as other objects in view, the invention resides in the novel features of 15 construction and combinations and arrangements of parts as more fully hereinafter set forth.

In the drawings:—

Figure 1 is an interior side elevation of 20 a vehicle door, broken away, to show our invention;

Figures 2 and 3 are cross sections respectively on the lines 2—2 and 3—3 of Figure 1;

Figure 4 is an enlarged side elevation of 25 the upper runway;

Figures 5 and 6 are cross sections respectively on the lines 5—5 and 6—6 of Figure 4.

The frame in which the window is slidably mounted is formed in the present instance 30 by a vehicle door having the pillars 1 and 2 and the lock board 3 with the window opening above the lock board and a chamber below the opening adapted to receive the window 4 when lowered from a position closing the 35 opening. This window is a sashless glass.

For guiding the glass, pairs of upper and lower runways 5 and 6 are provided with the upper runways overlapping the glass when in its lowermost position and the lower 40 runways abutting the upper runways. The lower runways are formed of the sheet metal channel-shaped strips 7, which are secured to the pillars 1 and 2, and the fabric linings 8, preferably felt, which are permanently se- 45 cured to the strips 7 as by being cemented thereto. 9 are rolls of relatively large diameter engaging the channel-shaped linings and rotatably mounted upon the brackets 10 which are rigidly secured to the ends of the 50 channel 11 embracing and fixed to the lower

edge of the glass 4. These rolls, being relatively large, present a relatively large distance between the periphery of each roll engaging the runway and the adjacent edge of its supporting bracket, thereby taking care of 55 large variations in distances between the pillars, as well as large variations in width of the glass.

The upper glass runways 5 are constructed to be highly flexible to take care of relatively 60 large variations in the thickness of the glass, as well as provide for commercial assembling misalignment of the lower runways with the upper runways. Also, these upper runways are constructed to have the minimum frictional engagement with the glass. Furthermore, the upper runways are constructed to 65

take care of relatively large variations in the width of the glass. As shown, each runway has the sheet metal retainer strip 12 with its base secured to one of the door pillars and with transverse side flanges 13. 14 are sheet metal L-shaped side strips having their inner portions located in the retainer strip and formed with the foot flanges 16 engaging the outer face of the base of the retainer strip. 70

The outer portions 17 of these side strips converge outwardly from their inner portions and terminate in the rounded beads 18. 19 is a resilient strip preferably formed of rubber and located in the retainer strip and engaging the outer faces of the foot flanges 16 to resiliently hold the outer portions of the side strips in predetermined positions relative to each other, these positions being 75

termed the normal positions. 20 is a lining, preferably formed of felt, this lining being of general channel-shape and having its base fixedly secured to the outer face of the resilient strip 19 as by stitching and its side portions fixedly secured to the outer portions 17 of the tension strips 14 as by being clamped to the side strips by the beads 18. These side portions of the lining converge outwardly 80 from its base and terminate in beaded portions surrounding the beads 18 of the side strips. For securing the resilient strip 19 to the retainer strip 12 and thereby securing the side strips 14 in place, the side flanges 13 85 of the retainer strip are provided at longi- 90

190

tudinally spaced points with the tongues 21 which are bent inwardly over the resilient strip to clamp the same to the base of the retainer strip. These tongues extend 5 through the slots 22 in the inner portions of the side strips, which slots form the inner portions of the side strips into longitudinally spaced sections. The slots are appreciably wider than the tongues so that the portions 10 of the resilient strip between the edges of the tongues and the edges of the sections are sufficiently long to provide for flexing through a considerable angle, thereby permitting the outer portions of the tension strips to move away from each other through 15 a relatively wide range. As a result, the upper runways are adapted to take care of a large variation in thickness of the glass and at the same time oppose the minimum frictional resistance to its movement by reason 20 of the fact that the portions of the lining engaging the opposite side of the glass are rounded to have a single line contact therewith. With the arrangement of side strips 25 having outer beaded edges and yieldably held in place by the resilient strip, the depth of the runway may be relatively great to take care of large variations in the width of the glass or in the distances between the pillars 30 without liability of the glass jumping out of the runway or of the seal between the runway and glass being destroyed.

As shown particularly in Figure 5, the window frame has its channel, in which the upper runways are located, formed of two relatively movable members, the one being a pillar and the other a removable trim mold 23, which is adjustably secured to the pillar. The transverse side flanges 13 of the retainer 40 strip of the upper runway form rigid stops which are engageable with the shoulders formed by the pillar and the trim mold to limit the movement of these shoulders toward each other and to prevent the same from affecting in any way the operation of the side strips 14 and the lining 20, so that assembly 45 is facilitated since there is no possibility of increasing the friction between the runway and the glass.

From the above description, it will be readily seen that we have provided a guideway for a glass which is so constructed that it opposes the minimum frictional resistance to movement of the glass. It will also be 55 seen that the guideway and particularly the upper runways forming part of the guideway takes care of large variations in thickness and width of the glass. It will furthermore be seen that the upper runway being 60 very flexible permits misalignment of the lower guideways with the upper guideways and still maintains a good seal.

What we claim as our invention is:

1. A window runway including a flexible channel-shaped lining having its sides

formed with rounded portions for engaging the opposite sides of the window, members engaging the rounded portions for holding the same in their normal positions, the members being yieldably held in place to permit movement of the rounded portions from their normal positions away from each other, and a retainer for the lining and members independent of the window frame providing stops at the opposite sides of said lining and members to prevent movement of the rounded portions by the parts of the window frame to which the runway is secured. 70

2. A window runway including a lining having a flexible side portion for engaging a side of the window, a member engaging the side portion, means separate from said member for resiliently holding the member in place, and a retainer adapted to form a unit with the lining, member and means. 80

3. A window runway including a flexible channel-shaped lining having side portions for engaging opposite sides of the window, side members at the opposite sides of the lining and engaging the side portions, resilient means between said lining and said members and engaging the latter for holding the side members in place, and a retainer for the lining, side members and resilient means. 90

4. A window runway including a channel-shaped lining having a flexible side portion for engaging a side of the window, a side member engaging the flexible side portion, the side member having a foot flange spaced from and extending substantially parallel to the base of the lining, a resilient strip between the base of the lining and the foot flange and engaging the latter to resiliently hold the side member in place, and a retainer for the lining, side member and resilient strip. 95

5. A window runway including a flexible channel-shaped lining having beads at the outer edges of its side portions for engaging the opposite sides of the windows, L-shaped side members having portions at their outer edges for engaging the beads and having foot flanges at their inner edges, a resilient strip between the base of the channel and the foot flanges and engaging the latter to resiliently hold the side members in place, and a retainer for the lining, side members and resilient strip. 105

6. A window runway including a flexible channel-shaped lining having side portions for engaging the opposite sides of the window, sheet metal L-shaped strips having continuous portions engaging the side portions and interrupted inner portions having longitudinally spaced sections formed with foot flanges extending substantially parallel to and spaced from the base of the lining, a resilient strip between the base of the lining and the foot flanges and engaging the latter to resiliently hold the L-shaped strips in place, and a retainer embracing the inner 110 120 125 130

portions of the L-shaped strips and having tongues longitudinally spaced from the edges of the sections and engaging the resilient strip to secure the same and the L-shaped strips to the retainer.

5. 7. In a window runway, individual side members spaced from and movable relative to each other, means for resiliently holding said members in their normal positions, said 10 means being yieldable to permit movement of said side members from their normal positions away from each other, and a retainer for said side members and said resilient means independent of the window frame providing 15 stops at the opposite sides of said side members and resilient means to prevent movement of the side members by the parts of the window frame to which the runway is secured.

8. In a window runway, individual side 20 members spaced from and movable relative to each other, a resilient strip between said side members and engaging portions thereof to resiliently hold said members in spaced relation to each other and a retainer for said 25 side members and resilient strip independent of the window frame.

9. A window runway including means having opposed portions for engagement with the opposite sides of the window, one of the 30 opposed portions being movable relative to the other, means for resiliently holding the movable portion in a normal position relative to the other, the last-mentioned means being yieldable to permit movement of the movable 35 portion from its normal position away from the other portion, and a retainer for both of the means providing a stop to prevent movement of the movable portion by the parts of the window frame to which the runway 40 is secured, said retainer having means engaging said resilient means for securing the same and said movable portion to the retainer.

In testimony whereof we affix our signatures.
